UNITED STATES PATENT OFFICE.

DONALD W. KELLEY, OF ONEIDA, NEW YORK.

PROCESS OF PRODUCING BEARING-APERTURES IN TRAP-SPRINGS.

1,272,051.

Specification of Letters Patent.

Patented July 9, 1918.

Application filed June 24, 1914. Serial No. 846,973.

To all whom it may concern:

Be it known that I, DONALD W. KELLEY, residing at Oneida, in the county of Madison and State of New York, have invented certain new and useful Improvements in Processes of Producing Bearing-Apertures in Trap-Springs, of which the following is a specification.

This invention relates to an improvement 10 in animal traps, and particularly that class of traps commercially known as "steel" traps. These traps employ a pair of pivoted jaws movable to gripping position under the impulse of a powerful leaf spring which is 15 formed with a bearing part arranged to slide along leg portions of said jaws.

The particular object of the invention is to improve the formation and construction 20 of the bearing portion of the spring, the improvement being directed toward facilitating a smoother and quicker operation of the spring and jaws, and toward improving the wearing qualities of the jaws and of the engaging or bearing portion of the spring.

25 A more particular object is to provide a condensed and hardened, smooth and rounded, surface upon the bearing portion of the spring.

The invention particularly relates to a new 30 and improved process by which the above results may be obtained.

Other objects and aims of the invention, more or less specific than those referred to above, will be in part obvious and in part 35 pointed out in the course of the following description of the elements, combinations, arrangements of parts and applications of principles, constituting the invention; and the scope of protection contemplated will be 40 indicated in the appended claims.

In the accompanying drawings which are to be taken as a part of this specification, and in which I have shown a merely preferred form of embodiment of the invention.

45 Figure 1 is a perspective view of a spring constructed in accordance with the provisions of this invention, and illustrating in dotted lines the complete trap in connection with which the spring is utilized;

50 Fig. 2 is an enlarged transverse, sectional view illustrating a portion of the spring in the process of formation;

Fig. 3 is a view similar to Fig. 2, illustrating a further step in the production of 55 the improved spring;

Fig. 4 is an enlarged, transverse, sectional

view of that portion of the spring operated upon in the steps shown in Figs. 2 and 3; and

Fig. 5 is a plan view of that portion of the 60 spring illustrated in Fig. 4, and illustrating that portion of the spring with which this invention deals when said portion is in its completed condition ready for use.

Referring to the drawings for a detailed 65 description of the invention, the reference character L indicates the spring of the trap. This spring is formed of a single sheet of metal bent upon itself to V-shape, and the opposite ends of the V are enlarged and provided with apertures as H and 2. The aperture H is designed to engage about a portion 70 of the trap as clearly seen in Fig. 1, and the aperture 2 is designed to slide longitudinally 75 upwardly along the legs 3 of the jaws 4 of the trap for swinging said jaws together in a well understood manner which need not be further described here.

In this operation the edge surfaces of 80 the material of the spring L which define the aperture 2 obviously engage against the edge surfaces of the legs 3, and the ease with which these edge surfaces move relatively to each other depends to a considerable extent upon the decree of friction set up therebetween. As ordinarily constructed the aperture 2 is formed by simply punching out a portion of the material. This operation, as heretofore performed, leaves sharp and ragged edges for engaging the legs 3. Such 85 90 ragged and sharp edges cause a certain degree of mutilation of the legs 3 and result in a more or less defective structure.

By my improved method of punching the 95 aperture 2 the edges of said aperture are rounded as clearly illustrated in the steps shown in Figs. 2 and 3 of the drawings. In these figures it is seen that the punch as G is formed of two diameters, and the shoulder between said diameters is concavely 100 rounded as at 5. This rounded shoulder is brought into engagement with the edge 6 of the aperture as the punch moves downwardly, and presses the material of said edge backwardly into the remainder of the 105 structure. The compression of material in this operation of rounding the edge 6 produces an appreciable condensation of the molecules of metal adjacent the inner surface of the aperture, and a consequent hardening thereof, so that not only is the confining wall of the aperture rounded and 110

smoothed in conformity with the shape of the portion 5 of the punch G, but said confining walls are simultaneously hardened.

- In this way the surface of the aperture 2 which engages the legs 3 of the jaws 4 is made capable of moving along said legs with a minimum of friction and with little likelihood of mutilation either of the walls of the aperture or of the legs of the jaws.
- 10 Special attention may be directed to the fact that the legs 3 of the jaws are provided with enlargements as at 7, for the purpose of receiving the upward blow from the spring when the trap is released. Owing to the fact that the jaws 4 are usually cast of malleable iron, the enlargements 7 present rounding corners for receiving the blow from the spring. When the impacting portion of the spring is allowed to retain a sharp corner at the upper end of the aperture, as is the present universal practice, such sharp corner bites or digs into the relatively soft rounding corners of the enlargements 7, and, after a few operations, causes portions of the material of said rounding corners to be cut and curled up to a greater or less extent. This curled up material forms a sharp knife-like edge, and is the source of much annoyance and danger in handling the trap. It is apparent, however, that when the upper end of the aperture, forming the impacting portion of the spring, is rounded and the entire wall surface of the aperture or bearing is hardened as in accordance with the present invention, such cutting of the material of the jaws is obviated.
- 15 20 25 30 35

While the drawings and description comprising this application are particularly

directed to the manufacture and use of a spring for animal traps, it is, however, apparent that the rounded and hardened bearing formed upon the spring may as well be formed upon other articles than springs, and in fact, rounded and hardened bearings of the type described may be manufactured for numerous purposes within the scope of this invention.

It is of course intended that all matter contained in the above description, and shown in the accompanying drawing, shall be interpreted as illustrative only, and not in a limiting sense, and that the following claim is intended to cover all the generic and specific features of the invention which may be said to fall within the language of said claim.

Having thus described my invention what I claim as new and desire to secure by Letters Patent, is:

The herein described process of producing a bearing aperture in a spring for animal traps, which consists in first forming an aperture at one end of the spring, the walls of said aperture being substantially at right angles to the upper surface of said spring, and then pressing the upper annular corner portion of the walls of said aperture to make said corner portion round and smooth and to condense and harden said portion.

In testimony whereof I affix my signature in the presence of two witnesses.

DONALD W. KELLEY.

Witnesses:

W. SCHNEELOCH,
SIGRID AHRENS.
